(57) **CLAIM**

I claim the ornamental design for the coating transfer device, as shown and described.

DESCRIPTION

FIG. 1 is a front view of the coating transfer device with the protection cap in a protective position;

FIG. 2 is a rear view thereof;

FIG. 3 is a top view thereof;

FIG. 4 is a bottom view thereof;

FIG. 5 is a side view thereof;

FIG. 6 is a perspective view of the coating transfer device with the protection cap in a partially opened position;

FIG. 7 is a front view of the application head with the protection cap in a fully opened position;

FIG. 8 is a rear view thereof;

FIG. 9 is a top view thereof;

FIG. 10 is a bottom view thereof;

FIG. 11 is a side view thereof;

FIG. 12 is an enlarged partial front view of the protection cap of the application head shown separately for completeness of illustration;

FIG. 13 is a rear view of FIG. 12;

FIG. 14 is a top view of FIG. 12;

FIG. 15 is a bottom view of FIG. 12;

FIG. 16 is a right side view of FIG. 12; and,

FIG. 17 is a left side view of FIG. 12.

The broken line showing of the elements of the coating transfer device is for the purpose of illustrating portions of the body of the device and forms no part of the claimed design.
